UNITED STATES PATENT OFFICE.

WILLIAM L. WEBER, OF CHICAGO, ILLINOIS.

ANNUNCIATOR.

1,195,754.

Specification of Letters Patent. Patented Aug. 22, 1916.

Application filed February 4, 1915. Serial No. 6,003.

To all whom it may concern:

Be it known that I, WILLIAM L. WEBER, a citizen of the United States, residing at Chicago, in the county of Cook and State of Illinois, have invented certain new and useful Improvements in Annunciators, of which the following is a specification.

This invention is a device in the nature of an annunciator, designed for use mainly 10 in restaurants, cafés and similar establishments.

The main object of the invention is to provide a simple and practical device for facilitating the filling of orders from the 15 dining room, to eliminate noise and clamor resulting from the verbal transmission of orders from the dining room to the kitchen, to avoid the likelihood of error and oversight in the transmission and filling of such 20 orders, and generally to improve the service.

To these ends my invention consists in a mechanical annunciator through the agency 25 of which, as soon as an order is received by a waiter it is noiselessly announced in the kitchen, and whereby a record is maintained in the kitchen of duplicate orders for any one article in such a manner that the cook may ascertain at a glance the exact number 30 of orders for such article waiting to be filled.

In its essential features the device comprises an annunciator board located in the kitchen within plain view of the cook, bearing labels corresponding to the various articles or items on the menu card, and, in association with each label, is a movable device 35 adapted to bring successively into view successive numerals, each indicative of the number of unfilled orders for that article received in the kitchen. This movable device 40 is preferably actuated step by step by electrical means through a circuit closed by the waiter in the dining room upon receipt of the order; and, as soon as an order has been 45 filled, the cook actuates a device whereby the numerical annunciator device is set back one number. I preferably employ in association with each of said devices on the annunciator board a visual signal, such as a lamp, which 50 burns continuously so long as any order for the article with which it is associated remains unfilled, but is automatically extinguished as soon as there are no orders for such article remaining unfilled.

55 The device of my invention, its mode of use, and the advantages resulting therefrom

will all be readily understood when considered in connection with the accompanying drawings wherein I have illustrated one practical embodiment of the device, and in 60 which—

Figure 1 is a front elevation of a fragment of the annunciator board; Fig. 2 is a similar view, enlarged, illustrating one of the annunciator sections; Fig. 3 is a vertical section through one compartment or section of the annunciator board illustrating the removable annunciator mechanism contained therein seen on the line 3—3 of Fig. 5; Fig. 4 is a similar section as seen on the line 4—4 of Fig. 5, the armature and pawl operated thereby being shown in normal inoperative position; Fig. 5 is a horizontal section through one of said compartments, showing the annunciator mechanism in top plan view, the armature and pawl being shown in position at the end of their operative stroke; Fig. 6 is a diagrammatic view illustrating the circuits of the operating magnet and lamp of the annunciator mechanism; Fig. 7 is a diagrammatic view, somewhat more in detail than Fig. 6, illustrating the circuit of the annunciator lamp.

Referring to the drawings, 10 designates a vertical wall which may be one of the walls of the kitchen, or the vertical wall of a specially constructed cabinet for the annunciator board, and 11 designates each of a group of horizontal shelves mounted on and projecting forwardly of the back wall 10, the space between said shelves 11 being divided by vertical partitions 12 into a series of rectangular compartments. To the front of the bottom wall of each compartment is secured a label holder 13 containing a card 95 or label 13' on which is printed the name of one of the dishes served in the establishment.

Within each compartment are housed the principal parts of the annunciator mechanism, as follows: 14 designates as an entirety a rectangular metal box of a size to slidably fit within the compartment, being entered through the open front end of the latter and, at its rear end abutting against a stop 15. Secured to the bottom wall of the box 14 are a pair of standards 16 journaled in and between the upper ends of which is a shaft 17 on which is keyed an annunciator wheel or disk 18 having a polygonal periphery, each face of which bears a numeral, as shown in Fig. 5, the numerals

being arranged in successive order from zero up. A wheel having ten faces bearing the numerals 0 to 9 inclusive is herein shown, but obviously the number of faces and corresponding numerals employed is immaterial. In the front wall of the box is an opening 19 (Fig. 2), through which the numerals on the faces of the annunciator wheel show as they are brought into register with said opening. Suitably mounted in the box, in rear of the annunciator disk is an electromagnet 20, herein shown as a twin spool magnet, with which co-operates an armature plate 21, the ends of which are formed with forwardly extending ears 22 that are secured to the vertical limbs 23 of a bail-shaped member 24 that, in turn, is journaled near its lower end on a pivot shaft 25, in turn mounted in a pair of upstanding lugs 26 on the bottom of the box. One of the arms 23 is somewhat longer than the other, and pivotally connected to its upper end is a hook 27, the free end of which rides over and engages the teeth of a ratchet disk 28 (Fig. 4) keyed on the shaft 17. The upper inclined edge 27' of the free end of the hook 27 is confined by a keeper 29 that may conveniently be formed as a bent-over portion of the upper end of one of the standards 16, and which serves to prevent overthrow of the annunciator wheel. The bail-shaped member 24 which carries the hook 27 and the armature plate is normally urged in a direction away from the core of the magnet and toward the annunciator disk by a spring 30 anchored at its lower end to the pivot shaft 25, and at its upper end engaging the arm 23 that carries the hook 27. From the foregoing it will be seen that each time the magnet is energized the hook 27 will be actuated in a rearward direction, thereby turning the annunciator disk 18 to an extent corresponding to the angular distance between two adjacent teeth of the ratchet disk 28, this corresponding to the angle subtended by one face of the annunciator disk. To prevent back-throw under the return movement of hook 27 the shaft 17 is provided with a metal brake disk 31, the periphery of which is engaged by a spring arm 32 (Fig. 4) mounted on an insulated post 33 and serving as a brake shoe. Incidentally, it may here be mentioned that the brake disk 31 and arm 32 perform a further function in connection with the circuit of the signal lamp, as will be later described, and for which purpose the metal disk 31 is provided at one point in its periphery with an insert 34 of insulated material; this insert 34 engaging the shoe of the arm 32 to interrupt the signal lamp circuit when the blank or zero face of the annunciator disk 18 registers with the sight opening 19.

On the other end of the shaft 17 is keyed another ratchet disk 35 (Fig. 3), the teeth

of which face in a direction opposite to those of the ratchet disk 28. Co-operating with the ratchet disk 35 is a dog 36 that is pivoted at 37 to a dog-carrier 38 that, in turn, is fast on a push rod 39 mounted to slide in the front wall of the box and in an upstanding bracket 40 secured to the bottom wall of the box. A spring 41 surrounding the rod 39 and abutting at one end against the bracket 40 and at its other end against a collar 42 pinned to the rod, normally urges the latter in an outward direction. The dog 36 has a tooth 43 adapted to engage the teeth of the ratchet disk 35 and is normally urged toward the latter by a spring 44, but, in the fully retracted position of the push rod 39, is held out of engagement with the ratchet disk 35 by a stop 45. The dog 36 also has a notch 46 adapted to co-operate with the ratchet disk upon the advance movement of the dog in a manner to prevent overthrow. On the outer end of the push-rod 39 is a knob or button 47. From the foregoing it will be evident that when the rod 39 is pushed inwardly, the dog 36 will engage the ratchet disk 35 and turn the latter one step backwardly or in a direction of rotation the opposite of that effected by the magnet; the directions of rotation effected by these agencies being indicated by arrows on Figs. 3 and 4.

Secured to the rear end of the magnet 20 is an upstanding plate 48 of fiber board or other insulating material, upon which latter are mounted three binding posts 49, 50 and 51, respectively, carrying spring contact arms 52, 53 and 54, respectively of a generally U-shape. In a cut out portion of the back wall 10 of the annunciator board are secured three contact members 55, 56 and 57, respectively, terminating in rounded heads 55', 56' and 57', that, when the box containing the annunciator mechanism is fully entered within its compartment, are engaged between the arms of the spring contacts 52, 53 and 54, as clearly shown in Fig. 5.

At any suitable location within the dining room convenient of access to the waiters, such, for instance, as the inner side of a lunch counter, is a group of labels corresponding to those on the annunciator board; and associated with each is a push-button that controls the circuit through the magnet of the annunciator mechanism of the particular dish indicated by the label. Referring to the diagrammatic view, Fig. 6, 58 designates such push-button mounted on a contact strip 59 that is normally separated from a co-operating contact strip 60. The magnet circuit may be traced from one side of battery 61 through the wire 62 (in which is included the contact strips 59 and 60), to the contact 55, thence through contact strip 52 and binding post 49, to and through the windings of the magnet 20, thence through

binding post 50 and contact strips 53 and 56 to circuit wire 63 leading into the other side of the battery 61. When the push-button 58 is pressed the circuit is closed at contact strips 59, 60, and the magnet energized.

In the front wall of the box is mounted a small electric lamp 64. Referring to Figs. 6 and 7, one terminal of the lamp is connected by a circuit wire 65 directly to binding post 51, the circuit extending thence through contact 54 to contact 57 and thence by line wire 66 to one side of the battery. The other terminal of the lamp is grounded to the frame of the box 14, and the circuit is completed through said box, standard 16, shaft 17, brake disk 31, metal brake arm 32, binding post 67, and line wire 68, the latter leading to binding post 50, and thence through contacts 53 and 56 and wire 63 to the other side of the battery. This lamp circuit is thus continuously closed except when interrupted by engagement of the brake arm 32 with the insulated insert 34 of the disk 31.

In the practical use of the device, when an order is given by a patron to a waiter for a certain article, the waiter simply presses the button 58 that is associated with the label of that article in the dining room. Assuming that there is no previous unfilled order for this article in the kitchen the annunciator disk pertaining to this article stands at blank or zero with its lamp 64 unlighted owing to the break in the lamp circuit at 34. The closing of the circuit by the push-button energizes the magnet and advances the annunciator disk one step causing the numeral 1 to show through the opening 19 in the annunciator board in the kitchen, and at the same time lighting the lamp. As soon as the cook has filled the order, he pushes the knob 47 inwardly, which sets the annunciator disk back to zero and simultaneously extinguishes the lamp. If, before the first order is filled and delivered at the kitchen, a second order for the same thing is received, the annunciator disk is advanced another step, announcing two unfilled orders in the kitchen. Similarly, if one or more further orders are received before the previous orders have been filled, the annunciator disk is still further advanced, the lamp continuously burning. As soon as the cook has delivered the first order received, he presses the knob 47 and thereby sets the annunciator disk back one step, this being repeated until all of the orders have been filled, when the annunciator disk will stand at zero or blank, and the signal lamp will be extinguished. So long as the lamp associated with the label of any particular article is burning, the cook knows that there must be one or more unfilled orders for that article in the kitchen, and a glance at the opening 19 always shows the number of such orders waiting his attention. It will thus be seen

that the device of my invention not only does away with the objectionable shouting of orders back and forth between the dining room and kitchen but makes it impossible for any order to become lost in the confusion of a busy period. 70

Of course, the specific details of the apparatus shown and described may be widely varied by those skilled in the art without departing from the principle involved or lessening the benefits and advantages attained by the invention; and hence the latter is not to be considered as limited to the particular mechanism shown and described beyond the extent clearly indicated in specific claims. 80

I claim:

1. In an annunciator of the character described, the combination of an annunciator board having a plurality of supports; fixed 85 electric contact devices associated with each support; a corresponding plurality of annunciator mechanisms removably mounted as units on said supports respectively; each of said mechanisms including a movable member bearing a series of numerals arranged in numerical succession thereon, means including an electro-magnet, for moving said member step-by-step to bring the numerals thereon in increasing order 90 opposite a fixed point, other means for moving said member step-by-step in the reverse direction, and electric contact devices adapted to automatically engage with said fixed contact devices when the annunciator 95 mechanism is properly positioned on its support; a label associated with and mounted in proximity to each annunciator mechanism, a normally open circuit in which said contact devices and electro-magnet are included; and a manually operable circuit- 100 closer in said circuit. 105

2. In an annunciator of the character described, the combination of an annunciator board having a plurality of supports; fixed 110 electric contact devices associated with each support; a corresponding plurality of annunciator mechanisms removably mounted as units on said supports respectively; each of said mechanisms including a rotatable 115 disk bearing a series of numerals arranged in numerical sequence on its periphery, means, including an electro-magnet, for turning said disk step-by-step to bring the numerals thereon in increasing order opposite a fixed point, manually operable means for turning said disk step-by-step in the reverse direction, and electric contact devices adapted to automatically engage with said fixed contact devices when the annunciator 120 mechanism is properly positioned on its support; a label associated with and mounted in proximity to each annunciator mechanism; a normally open circuit in which said contact devices and electro-mag- 125 130

- net are included; and a manually operable circuit closer in said circuit.
3. In an annunciator of the character described, the combination of an annunciator board having a plurality of supports; fixed electric contact devices associated with each support; a corresponding plurality of annunciator mechanisms removably mounted as units on said supports respectively; each 10 of said mechanisms including a rotatable disk bearing a series of numerals arranged in numerical sequence on its periphery, means, including an electro-magnet, for turning said disk step-by-step to bring the 15 numerals thereon in increasing order opposite a fixed point, manually operable means for turning said disk step-by-step in the reverse direction, electric contact devices adapted to automatically engage with said 20 fixed contact devices when the annunciator mechanism is properly positioned on its support, a signal lamp, and a circuit make-and-break device controlled by the turning movements of said disk; a label associated 25 with and mounted in proximity to each annunciator mechanism; a normally open circuit in which certain of said contact devices and said electro-magnet are included; a manually operable circuit closer in said circuit; and another circuit in which other of 30 said contact devices, said signal lamp, and said make-and-break device are included.
4. In an annunciator device for restaurants and the like, the combination of an 35 annunciator board mounted in the kitchen and formed with a sight opening therein, a label designating an order to be filled located on the front of said board in proximity to said sight opening, a movable member bearing a series of numerals arranged in 40 numerical succession and indicating the numbers of orders received mounted in rear of said sight opening, electrical means operable from the dining room for moving said 45 member in one direction one step at each actuation to bring the numerals thereon in increasing order into view through said sight opening, a remote control for said
- electrical means, means operable from the kitchen for moving said member in the opposite direction to bring the numerals thereon in decreasing order into view through said sight opening while maintaining the annunciator in condition for forward operation from the remote control, a signal lamp mounted on said board in proximity to said label and sight opening, an electric circuit in which said lamp is included, and means for automatically interrupting said circuit when said order-indicating member is moved to a position indicating no order waiting to be filled.
5. In an annunciator device for restaurants and the like, the combination of an annunciator board mounted in the kitchen 50 and formed with a sight opening therein, a label designating an order to be filled 55 located on the front of said board in proximity to said sight opening, an annunciator disk bearing upon its periphery a series of numerals arranged in numerical sequence, said disk being rotatably mounted behind said sight opening in a manner permitting the numerals thereon to be successively brought into view through said sight opening as said disk is rotated, an electro-magnet, pawl-and-ratchet driving connections between said magnet and said disk, a normally open circuit in which said magnet is included, a circuit-closer for said circuit located in the dining-room, a slidably mounted bar located in proximity to said sight opening and operable from the kitchen, pawl-and-ratchet connections between said bar and said disk adapted to turn the latter 60 in a direction opposite to that in which it is turned by said magnet, a signal lamp mounted in proximity to said sight opening, an electric circuit in which said lamp is included, and a circuit make-and-break device 65 controlled by the turning movements of said disk.
